ADJUSTABLE GUIDE ARM

Samuel E. Hopper, Crafton, Pa.

Application September 20, 1949, Serial No. 116,806

1 Claim. (Cl. 4—57)

1
This invention relates to a guide arm for flush valves, and represents an improvement over the guide arm described and claimed in my previous Patent No 1,975,607.

An important object of the present invention is to provide a guide arm which will attach itself more firmly to the flush tube.

Another important object is to provide a means on the guide arm for preventing relative rotation between the gripping members during tightening of the connecting screw extending therebetween.

Another important object is to provide an improved guide arm which will be simpler with respect to the manufacture thereof.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

Referring to the drawings

Fig. 1 is a view of the improved guide arm partly in vertical section and partly in side elevation as it appears when mounted in a flush tank.

Fig. 2 is an enlarged perspective view of the guide arm.

Fig. 3 is a fragmentary top plan view.

Fig. 4 is a section taken on line 4—4 of Fig. 1.

Fig. 5 is a fragmentary vertical section through a modified form.

Referring to the drawings in detail, 5 is a conventional overflow tube found in an ordinary flush tank, this extending upwardly from the conventional flush tank base 6 on which seats the tank ball 8 secured to the lower end of the rod 7 connected to the rod 9 extending from the conventional trip lever mechanism, not shown, chain, or other actuating means.

The parts so far described do not constitute part of the present invention, these being simply conventional parts such as found in any regularly constructed flush tank.

In accordance with the present invention, the guide arm includes a body portion 10 having an enlarged upper end 11 providing a boss in which is formed the smooth walled opening 12 through which extends the screw 13, said enlarged upper end or boss being formed with the forwardly extended ears 14 for a purpose to become apparent hereinafter. The inner surface of the body portion 10, at the upper end of the body portion between the ears 14, is offset outwardly as at 15 to

2
provide a fulcrum or pivot on which rocks the gripping member 16, that cooperates with the body portion 10 in gripping the wall of a flush tube 5 therebetween. As may be noted from Fig.

5 1, the upper ends of both the gripping member 16 and the body portion 10 project above the upper end of the flush tube, and said upper end of the gripping member 16 pivots upon the offset 15 of the body portion 10. Immediately below the upper end, the gripping member 16 is formed with the threaded opening 17 in which threads the screw 13.

Formed integrally with the body portion 10 at the lower end thereof is the obliquely extended arm 18 terminating in the enlargement 19 formed with the opening 20 in which the rod 7 is loosely slidable, thus providing a guide for said rod 7.

It may now be noted that to apply the guide arm of the invention to a conventional flush tube 5, it is necessary only that one loosen the screw 13 slightly, whereupon the body portion 10 and the gripping member 16 can be slipped over the upper end of the flush tube wall. Downward movement of said body portion and gripping member is limited by the screw 13 which will engage the upper end of the wall of the flush tube.

Thereafter, it is necessary only that the screw 13 be tightened. As the screw 13 is tightened, the gripping member 16 is caused to pivot upon the offset 15, causing the tube-engaging portions of the inner surfaces of the body portion and gripping member 16 to tightly clamp the tube wall therebetween. In this connection, it will be understood that the opening 12 of the body portion 10 should be formed to a slightly larger diameter than the diameter of the screw 13, so that there can be relative pivotal movement between the body portion and the gripping member 16.

When the screw 13 has been turned home to its maximum extent, the flush tube wall will be tightly gripped between the portions of the device. In this connection, it has been found in practice that the flush tube wall will be gripped

45 by practically the entire surface areas of the body portion 10 and gripping member 16 that are disposed below the screw 13. This is distinguished from the guide arm set forth in the above-mentioned patent, wherein there is a central fulcrum, causing only the lowermost end of the gripping member to have contact with the tube wall.

The invention further eliminates the necessity of a rivet, and other more or less costly features of the previous device set forth in the patent.

With respect to the ears 14 above-mentioned,

it may be noted that these ears straddle the gripping member 16, and prevent relative rotation between the gripping member 16 and the body portion 10 when the screw 13 is being tightened.

Referring to Fig. 5, I have here illustrated a modified form wherein a gripping member 21 is formed adjacent its upper end with a recess 22. Adjacent the upper end of a body portion 23, there is formed on the inner face of said body portion a lug 24 adapted to extend into the recess 22. In this connection, the lug 24 is greater in length than the depth of the recess, and additionally, the recess is slightly greater in diameter than the diameter of the lug. As a result, the body portion 23 pivots upon the lug 24 during the tightening of the screw 13 for the purpose of clamping the members 21, 23 to the wall of the flush tube 5. At the same time, the lug 24 engaging in the recess 22 prevents relative rotatable movement between the members 21 and 23.

What is claimed is:

A flush valve guide member comprising an elongated body having a concave longitudinally extending overflow pipe-engaging seat on one side thereof, a downwardly and outwardly ex-

tending arm carried by the body adjacent the lower end and on the side thereof remote from the pipe seat, a flush valve guide carried by the arm remote from the body, a lug carried by the body adjacent the end thereof remote from the arm, said lug projecting laterally from the side of the body having the seat and forming a fulcrum above the seat, a gripping member bearing on the lug, a convex longitudinally extending overflow pipe-engaging surface on the gripping member and a clamp screw extending through the body between the lug and the arm and threaded into the gripping member for rocking said gripping member on said lug and drawing it against an overflow pipe engaged by the seat.
